UNITED STATES PATENT OFFICE.

EDWIN G. EVENSTA AND HENRY J. ANDERSON, OF MINNEAPOLIS, MINNESOTA.

LAUNDRY-TUB FAUCET.

1,393,103.

Specification of Letters Patent.

Patented Oct. 11, 1921.

Application filed April 21, 1921. Serial No. 463,140.

To all whom it may concern:

Be it known that we, EDWIN G. EVENSTA and HENRY J. ANDERSON, both citizens of the United States, residing at Minneapolis, 5 in the county of Hennepin and State of Minnesota, have invented certain new and useful Improvements in Laundry-Tub Faucets; and we do hereby declare the following to be a full, clear, and exact description of the 10 invention, such as will enable others skilled in the art to which it appertains to make and use the same.

Our invention has for its object to provide a simplified and improved laundry tub faucet, provided with a swinging nozzle and having a simple and efficient clamp adapting it to be securely attached to a laundry tub without defacing the tub and without the use of pipe support other than the said 20 clamp.

Generally stated, the invention consists of the novel devices and combination of devices hereinafter described and defined in the claims.

25 In the accompanying drawings which illustrate the invention, like characters indicate like parts throughout the several views.

Referring to the drawings:

Figure 1 is a plan view of a laundry tub 30 showing the improved faucet applied thereto, some parts being broken away;

Fig. 2 is an enlarged detail in section taken on the line 2—2 of Fig. 1;

Fig. 3 is a detail in section approximately 35 on the line 3—3 of Fig. 1;

Fig. 4 is a fragmentary vertical section illustrating, particularly, the construction of one of the valves;

Fig. 5 is a fragmentary view in vertical 40 section showing the swivel connection between the swinging nozzle and a body tube; and

Fig. 6 is a perspective showing the body tube and the separable members of the 45 clamp.

The numeral 7 indicates an ordinary two-compartment laundry tub. The numerals 8 and 9 indicate, respectively, the hot and cold water pipes which lead to the faucet.

50 The lower ends of these pipes 8 and 9 are provided with coupling unions 10 by which they are connected to the externally threaded upstanding nipples 11 of the horizontally disposed body tube 12 which, at its central

portion, has a third upstanding externally 55 threaded nipple 13. The ends of the nipples 11 are in communication with the interior of the tube 12 through ports 14 adapted to be opened and closed, at will, by valves 15 carried by the inner ends of valve stems 16. 60 The valve stems 16 have threaded portions 17 that work with threaded engagement in the outer end extension of the tube 12 so that the valves will be opened and closed by rotary movement. The end extensions of the 65 tube 12 are tightly closed around the valve stems by glands 18, and said valve stems, at their outer end, have detachable operating levers 19.

The clamp comprises two forked bracket 70 or clamp sections or members 20 and 21, the former of which is cast integral with the tube 12, and the latter of which is detachable therefrom. Adjacent to its connection with the tube 12, the bracket 20 has a flat surface 75 20^a formed with a longitudinal slot 20^b. At its upper portion, the bracket 21 has an offset flange 21^a and a further offset L-shaped lock lug 21^b. The flange 21^a is adapted to bear against the flat surface 20^a, and the angular 80 lock lug 21^b is adapted to be inserted through the slot 20^b, by an endwise rocking movement and to be securely interlocked therewith when the two brackets or members are secured together. 85

To rigidly, but detachably, connect the two brackets 20—21 together and to cause the prongs thereof to tightly clamp one edge of the tub on opposite sides of the partition of the tub, machine screws 22 are passed 90 through perforations 23 in the flat surface 20^a of bracket 20, and are screwed into internally threaded bosses 24 of the bracket 21. Thus the faucet structure is adapted to be securely anchored to the tub, and when thus 95 anchored, will support the lower ends of the hot and cold water supply pipe.

The swinging nozzle 25 is shown as provided with a short swivel tube 26 screwed into the receiving end thereof, and at its 100 lower end, having an annular flange 27 tightly seated against the upper end of the central nipple 13. The gland 28 screwed onto the nipple 13 and against the packing 28 seated on the flange 27, forms a water 105 tight joint and yet holds the nozzle 25 with freedom for swinging movement from one compartment to the other of the tub. With

this arrangement, hot and cold water, separately or simultaneously, may be delivered to either compartment of the tub.

This improved faucet structure, while of simple form and of small first cost to manufacture, is efficient for the purpose had in view, has few parts capable of getting out of order, and may be very easily repaired, when repairs become necessary.

10 What we claim is:

1. A faucet structure comprising a body tube with hot and cold water pipe connections and coöperating valves at its ends, a swinging nozzle connected to the intermediate portion of said body tube, and a tub engaging clamp made up of two brackets one of which is integral with said body tube and the other of which is detachably connected thereto, said brackets being laterally off-set in respect to each other and in respect to the body tube.

2. A faucet structure comprising a body tube with hot and cold water pipe connections and coöperating valves at its end, a swinging nozzle connected to the intermediate portion of said body tube, and a tub engaging clamp made up of two brackets one of which is formed as a part of said

body tube and the other of which is detachably connected thereto, one of said brackets having a slot and the other having a slot engaging lock lug insertible thereinto by an endwise swinging movement.

3. A faucet structure comprising a horizontal body tube with upstanding end nipples for hot and cold water connections and with an upstanding intermediate nipple, a swinging nozzle applied to said intermediate nipple, valves working in the opposite ends of said body tube for independently controlling the hot and cold water supply to the interior thereof and to said nozzle, a clamping bracket formed integral with said body tube and comprising a flat portion and depending clamping prongs, said flat portion having a slot, a detachable clamping bracket having depending clamping prongs and an offset flange with a still further offset approximately L-shaped lock lug, said lock lug being engageable with the slot of said first noted bracket, and screws connecting the two bracket members.

In testimony whereof we affix our signatures.

EDWIN G. EVENSTA.
HENRY J. ANDERSON.
